UNITED STATES PATENT OFFICE.

CHARLES B. MEADOWS, OF HOUSTON, TEXAS.

SUPERHEATER FOR OIL BURNERS.

Application filed November 27, 1923. Serial No. 677,241.

To all whom it may concern:

Be it known that I, CHARLES B. MEADOWS, a citizen of the United States, residing at Houston, in the county of Harris and State 5 of Texas, have invented certain new and useful Improvements in a Superheater for Oil Burners, of which the following is a specification.

This invention relates to new and useful 10 improvements in a heater for oil burners.

One object of the invention is to provide 15 a heater in combination with an oil burner, whereby the fuel will be heated by the steam before its delivery to the burner, and the steam, by means of which the fuel is sprayed 20 into the combustion chamber, will also be superheated in the combustion chamber before it passes through the burner to eject the oil.

Another object of the invention is to provide 25 a device of the character described which is of very simple construction, which may be cheaply manufactured, and which will conduce to an effective vaporization of the fuel, and consequently a more perfect combustion thereof.

With the above and other objects in view, this invention has particular relation to certain novel features of construction, operation, 30 and arrangement of parts, an example of which is given in this specification and illustrated in the accompanying drawings, wherein:

Figure 1 shows a plan view of the device 35 as applied to the combustion chamber.

Figure 2 shows a front elevation thereof, Figure 3 shows a side view; and,

Figure 4 shows an enlarged longitudinal 40 sectional view of the heater.

Referring now more particularly to the drawings, wherein like numerals of reference designate similar parts in each of the figures, the numeral 1 designates the furnace having the combustion chamber 2 therein.

The numeral 3 designates the oil burner of conventional construction, having an oil pipe 4 through which the fuel is delivered, and a steam pipe 5 through which steam is delivered, under pressure, to spray the oil 45 into the combustion chamber, in the usual

way. These pipes pass through front wall of the furnace and are anchored therein and anchor the burner in place.

The numeral 6 designates the heater shell, or jacket, and spaced within this jacket 55 there is a similarly shaped oil container 7. At one end the shell and jacket are closed and they are connected by a tubular bridge 8 into which the outer end of the oil pipe is connected. The other ends of the jacket 60 6 and container 7, are closed by the removable end plate 9, thus forming an enclosed oil chamber 10 within the container and a surrounding annular enclosed steam chamber 11 around said container. An oil supply 65 line 12 enters said oil chamber through said end plate. The outer end of the steam pipe 5 is connected through the jacket wall into said steam chamber 11, and a steam supply line 13 enters said steam chamber, and de- 70 liverers hot steam thereto.

It is to be noted that the steam line 5 passes from the shell 6 through the front wall of the furnace and is formed into a loop 14 in the combustion chamber above 75 the burner, and then passes out again through the front wall of the furnace, and is turned inwardly through said wall before entering the burner.

The hot steam in the chamber 11 heats 80 the fuel in the chamber 10 so that it will be delivered to the burner, through the pipe 4 in a fluent, and partly vaporous state and the steam passing through the coil 14 will be superheated before it passes through 85 the burner, and will eject the fuel from the burner into the combustion chamber and further vaporize it, thus rendering the fuel completely combustible so that it will all be consumed.

What I claim is:—

1. The combination with a combustion chamber and an oil burner therein, of a heater including an oil line formed with an enlarged chamber, a steam line formed with a jacket which surrounds and is spaced from said chamber, said lines terminating in said oil burner, said steam line being formed into a coil within said combustion chamber between the heater and burner. 95 100

2. The combination with a combustion chamber and an oil burner therein, of a heater associated with the burner and embodying an oil line formed with an enlarged chamber, a steam line formed with a jacket which surrounds said chamber, and is spaced therefrom, said oil and steam lines terminating in said burner, and a loop into which one of said lines is formed said loop

being located in the combustion chamber 10 between the heater and burner.

In testimony whereof I have signed my name to this specification in the presence of two subscribing witnesses.

CHARLES B. MEADOWS.
